SUDDEN PRESSURE RELAY TESTING DEVICE
Phillip W. Russell, 14015 Superior Ave., Cleveland, Ohio
Filed July 30, 1959, Ser. No. 830,608
10 Claims. (Cl. 73—4)

This invention relates to means for testing the internal components of electrical transformer sudden pressure relays, and more particularly relates to the testing of the tripping and resetting functions of the relay as well as the response times of these functions.

A sudden pressure relay is a protective device usually mounted on a side of a gas-cushioned, liquid immersed, electrical transformer in the region of the gas space, the transformer referred to being of the heavy duty industrial type used by utility companies and the like for handling high voltage electricity. A sudden pressure relay is designed for alarm-trip circuit closing on occurrence of a fault in the transformer which produces an abnormal rise of pressure. Inasmuch as this apparatus is factory sealed and not susceptible to direct manual inspection *per se*, it is normal procedure to remove the relay from the transformer and transport it to a laboratory where it can be tested by apparatus designed to simulate the functioning of a transformer. Once the sudden pressure relay is removed from the transformer, the transformer gas is lost to the atmosphere, resulting in downtime for the transformer until the relay can be returned, installed, and the transformer recharged with gas. With my invention, it is not necessary to remove the sudden pressure relay from the transformer, inasmuch as the invention is adapted to make all necessary checks right in the field of the internal components of the relay including the bellows means, the limit switch means, sub-relay means, and contacts associated with the sub-relay means.

The present customary method of checking sudden pressure relays includes the application of pressure under laboratory controlled conditions on the transformer side of the relay to determine the proper functioning of the internal mechanisms of the relay. It is my concept, however, to reverse this method and reduce pressure on the sudden pressure relay side of the transformer to achieve the same net influence upon the sudden pressure relay mechanisms. The degree of pressure decrease in the sudden pressure relay may be calibrated to achieve the same effect as a corresponding pressure increase on the transformer side. Inasmuch as a sudden pressure relay depends upon differential pressure for operation, it is, therefore, immaterial whether the increase of pressure be on the transformer side or a corresponding decrease of pressure be on the sudden pressure relay side.

It is, therefore, the general object of my invention to provide a field testing unit for inspecting and checking the functioning of sudden pressure relays without the necessity of removing the relay from the transformer resulting in all of the enumerated disadvantages of this procedure.

The features of this invention which are believed to be novel are set forth with particularity in the appended claims. The invention itself, however, both as to its organization and use, together with further objects and advantages thereof, may best be understood by reference to the following description taken in conjunction with the accompanying drawings in which:

FIGURE 1 is a perspective elevational view partly in section of a typical sudden pressure relay in association with a schematic representation of the subject invention; and

FIGURE 2 is a schematic wiring diagram of a preferred embodiment of my invention shown in association with the schematic wiring diagram of a sudden pressure relay.

2

Referring now to FIGURE 1 in greater detail, a typical sudden pressure relay 10 is shown to include a bellows 12, adapted to actuate a limit switch 14 connected to a seal-in sub-relay means 15. The sudden pressure relay is hermetically sealed to a mounting base 18 and isolated from the transformer mounting base 20 except for a small pressure equalizer plug 22. This equalizer plug 22 is provided with a small bore 24, permitting normal transformer operation over its entire pressure range without giving a false alarm. The pressure equalizer plug 22 will act to throttle any rate of pressure change of greater magnitude than that experienced in normal operation so as to effect a pressure differential between the relay case and the transformer case, and thus operate the bellows 12 and the pressure actuated limit switch 14.

The general organization of my invention includes solenoid operated valve means 30, connected directly to the sudden pressure relay 10 by suitable tube means 32 and connected to a plug 34 which is provided as standard equipment in the relay 10. I also connect to the electrical jack 50, which is also standard equipment with the sudden pressure relay 10, circuitry in association with timer means 36 and switch means S-3 adapted to energize the timer means 36 at the same time that the solenoid operated valve means 30 is actuated. The solenoid operated valve means 30 comprises, in a preferred embodiment of my invention, a plurality of valves 30a, 30b, 30c, and 30d, each of which is provided with a port to exhaust gas from the sudden pressure relay 10 to the atmosphere at a predetermined rate in pounds per second. Thus, by opening the solenoid valve 30a, for instance, the timer 36 is started and will continue to run until the pressure in the sudden pressure relay 10 drops to a predetermined level. At this time, the bellows 12 in the sudden pressure relay 10 will operate or expand to actuate the limit switch 14 and to stop the timer 36 by circuitry generally designated at 40 which I incorporate with the seal-in sub-relay 15 of the sudden pressure relay 10. The provision of extra solenoid operated valves 30b and 30c, having ports of different sizes enables the testing of sudden pressure relays having different timing constants. I also provide pilot light circuitry including pilot lights PL-1, PL-2, PL-3, PL-4, and PL-5 to monitor the operation of relay contacts C-1, C-2, C-3, C-4, C-5, and C-6 while at the same time testing the general functioning of the sub-relay 16.

To check the re-set time of the bellows 12, I provide circuitry which connects the sudden pressure relay 10 to a solenoid operated valve 30d providing substantially instantaneous exhaust capacity. Additionally, this circuitry also provides for a 15 second delay period for the purpose of assuring that all pressure has been released from the sudden pressure relay 10. Thereafter, the timer 36 is automatically started and will continue to run until the bellows 12 recovers its normal collapsed condition, thereby permitting the limit switch 14 to re-set. When the limit switch 14 re-sets, the timer then stops.

Referring now to FIGURE 2 in greater detail, the test unit circuitry of FIGURE 2 can be best described and understood by tracing through a typical test operation. Once my testing unit is connected to the sudden pressure relay 10, the following initial conditions will exist. An adaptor 44 is secured to the sudden pressure relay test plug 34 connecting the interior of the sudden pressure relay 10 to a manifold 48 of solenoid operated valves 30a, 30b, 30c, and 30d. Sudden pressure relay receptacle 50 is engaged by test unit plug 52 to form a coupling generally designated at 53 and connecting the seal-in sub-relay 15 of the sudden pressure relay with the circuitry 40 of the test unit. Switch S-1 is closed, switch S-2 is open, and switch S-3 is at the open or terminal

T-0 position. A source of power is applied across lines L1 and L2 and a pilot light PL-1 is connected across these lines to indicate that the power is on. In FIGURE 2 a separate source of power across lines L3 and L4 is shown inasmuch as sudden pressure relays may have different power requirements from the test unit itself. This arrangement, however, is optional. Associated with the separate power source lines L3 and L4 is a pilot light PL-2 provided to indicate when these lines are energized. Assuming the above stated initial condition, the circuitry may be traced from L1 through coupling 53 connection J, normally closed relay C-8, receptacle connection K, and pilot light PL-3 to line L2. The energization of pilot light PL-3 will indicate that coupling connections J and K and normally closed contact C-8 are functioning properly.

The bellows of each sudden pressure relay will have a manufacturer's specification time constant for expanding under the influence of a predetermined pressure. In order to check this time constant, the following procedure is followed with my test unit. Switch S-3 is placed at terminal position T-1 and switch S-2 is closed permitting power from L1 to pass through switch S-2, terminal T-1 to magnetic valve 30a. Magnetic valve 30a is then energized to open an exhaust port which will decrease the pressure from sudden pressure relay 10 at a rate simulating a pressure buildup in the transformer. At the same time, the energy from line L1 will pass through coupling connection G, normally closed contact C-4, coupling connection H, switch S-2, terminal T-1, and normally closed contact C-3 to the Y terminal of the timer 36, thereby activating the timer. If the timer runs, it is then determined that coupling points G, H, and normally closed contacts C-3 and C-4 are functioning properly for this portion of the test.

When the pressure in the sudden pressure relay 10 is reduced to a predetermined level sufficient to cause the bellows to expand, limit switch 14 is closed permitting energy from L4 to pass through coupling connection A, limit switch 14, and sub-relay 16. When sub-relay 16 is energized, contacts C-5, C-6, C-7, and C9 will close and contacts C-4 and C-8 will open. When contact C-4 opens, the timer circuitry will be interrupted and the timer will stop. This tests the contact C-4 open condition and, at the same time, pilot light PL-3 will go out thereby verifying the open condition of contact C-8. Pilot light PL-4 will be energized through contact C-7 and coupling connection E, thereby testing these two units. At the same time, pilot light PL-5 will be energized through coupling connection D, contact C-6 and coupling connection L to test these units. This completes the test for the switch S-3 in the terminal T-1 position. In order to repeat the test, or in order to test the relay for a different time differential, switch S-3 is moved to the terminal T-0 position and switch S-1 is opened. Magnetic valve 30a will then close and the pressure in the sudden pressure relay 10 will then build up by virtue of bleeding through the bore 24 in equalizer plug 22 connecting the sudden pressure relay to the transformer. After the pressure differential has decreased sufficiently, the bellows 12 will commence to collapse again into its normal position and limit switch 14 will open to de-energize sub-relay 16. When sub-relay 16 is de-energized, pilot light PL-4 and pilot light PL-5 will go out and pilot light PL-3 will re-light. Switch S-2 is then reopened and sufficient time is then allowed for the pressure equalization between the sudden pressure relay and the transformer before making the next test. In order to test the sudden pressure relay for other time constants, such as determined by magnetic valves 30b and 30c, the above procedure is repeated by placing switch S-3 in terminal positions T-2 and T-3, respectively.

The other test of significance is that of timing the bellows 12 to determine if it collapses within the prescribed time set by the manufacturer after pressure has

become equalized between the sudden pressure relay 10 and the transformer. To begin the test, the test unit is put in the initial test status as described hereinabove. Switch S-3 is then placed in the terminal T-4 position, switch S-1 is opened and switch S-2 is closed. Sub-relays 60 and 62 are then energized across lines L1 and L2 through normally closed contact C-1. Sub-relay 62 will operate to open contact C-3, thereby removing power from the timer 36, and contact C-2 will close to energize magnetic solenoid valve 30d. Magnetic valve 30d is then opened to substantially instantaneously exhaust the pressure from sudden pressure relay 10. Sub-relay 16 will again be energized by the closing of limit switch 14, and sub-relay 60, which is a 15 second delay relay, will open contact C-1 at the end of the delay period. This will de-energize sub-relay 62, thereby causing contact C-2 to open and de-energize magnetic valve solenoid 30d. Concurrently, power is applied to the timer 36 through contact C-3, enabling the timer to run until the pressure in the sudden pressure relay 10 is sufficiently high to collapse bellows 12 and open limit switch 14. When limit switch 14 opens, sub-relay 16 will be de-energized and contact C-9 will open removing power from the timer. This then completes the re-set test. By observing the time logged by the timer, in both the bellows expanding test and the bellows re-set test, it is possible to determine whether the bellows are functioning in accordance with manufacturer's specifications. At the same time, all of the internal elements of the sudden pressure relay are monitored and checked for opening and closing conditions.

In summation, my invention provides the advantages of a device which is compact and portable, thereby making it available for use in the field; it is efficient and economical to operate, and requires less man power for operation; it eliminates the necessity for removing the sudden pressure relay from the transformer, thereby insuring practically no loss of gas pressure in the transformer; and it eliminates transformer downtime and labor costs involved in removing, testing and replacing sudden pressure relays. My invention is also simple in principle, thereby making it possible for personnel with a minimum of instruction and training to satisfactorily use the equipment.

While only one embodiment of my invention has been disclosed and discussed hereinabove, still other arrangements and modifications will appear to those skilled in the art upon a reading of the specification taken in conjunction with the drawings, and other arrangements may be resorted to without departing from the spirit and scope of the invention as defined by the appended claims.

I claim:

1. A testing device for a gas filled, positive pressure operated transformer sudden pressure relay of the class described having pressure sensitive means, said testing device comprising: a plurality of preset solenoid valve means selectively communicable with the interior of said sudden pressure relay to exhaust pressure from the interior thereof at a predetermined rate; timing means; and means to open one of said valve means and to start said timer; and means responsive to the actuation of said pressure sensitive means to stop said timer.

2. A testing device for a gas filled, positive pressure operated transformer sudden pressure relay of the class described having pressure sensitive relay means, said testing device comprising: means to exhaust pressure from the interior of said sudden pressure relay at a predetermined rate including preset solenoid valve means communicable with the interior of said sudden pressure relay; timing means; means to simultaneously open said valve means and start said timer; and means responsive to the actuation of said pressure sensitive relay means to stop said timer.

3. A testing device for a gas filled, positive pressure operated transformer sudden pressure relay of the class

described, having pressure responsive means, said testing device comprising: means to exhaust pressure at a predetermined rate from the interior of a said sudden pressure relay; timing means; first test means including means to simultaneously open said exhaust means and to start said timing means; and means to stop said timing means responsive to a first actuation of said pressure responsive means; second test means including means to simultaneously open said exhaust means and to deactivate said timing means; means responsive to a first actuation of said pressure responsive means to simultaneously close said exhaust means and to activate said timing means; and means responsive to a second actuation of said pressure responsive means to deactivate said timer.

4. A testing device for a gas filled, positive pressure operated transformer sudden pressure relay of the class described having pressure responsive means, said testing device comprising: first preset valve means adapted to exhaust pressure from said sudden pressure relay at a controlled rate; second preset valve means adapted to substantially instantaneously exhaust pressure from said sudden pressure relay; timing means; first test means circuitry including means to simultaneously open said first valve means and to start said timing means; and means to stop said timing means responsive to a first movement of said pressure responsive means; second test means circuitry including means to simultaneously open said second valve means and to deactivate said timing means; means responsive to a first movement of said pressure responsive means to simultaneously close said second valve means and to activate said timing means; means responsive to a second movement of said pressure responsive means to deactivate said timer; and means to select and connect either said first test means circuitry or said second test means circuitry to said first or second valve means, respectively.

5. A testing device for a gas filled, positive pressure operated transformer sudden pressure relay of the class described having pressure responsive bellows means adapted to close and open limit switch means responsive to bellows means expansion and contraction movements respectively, said testing device comprising: an exhaust manifold including normally closed first and second solenoid valves, said first solenoid valve being preset to exhaust pressure from said sudden pressure relay at a predetermined controlled rate, said second solenoid valve being preset to exhaust pressure from said sudden pressure relay substantially instantaneously, means to connect said manifold to the interior of said sudden pressure relay; timing means; power means; first circuitry means including selector switch means connecting said power means to said first circuit means to simultaneously energize and open said first solenoid valve and energize and start said timing means; and means to de-energize said timing means responsive to expansion of said bellows means; second circuitry means; said selector switch means being adapted to disconnect said first circuitry means and to connect said second circuitry means to said power means to simultaneously open said second solenoid valve and to deactivate said timing means; means responsive to expansion of said bellows means to simultaneously close said exhaust means and to activate said timing means; and means responsive to contraction of said bellows means to deactivate said timing means.

6. A testing device for a gas filled, positive pressure operated transformer sudden pressure relay of the class described having pressure responsive bellows adapted to close and open limit switch means responsive to bellows expansion and contraction movement respectively, said testing device comprising: an exhaust manifold including preset, normally closed first and second solenoid valves having different exhaust rate capacities; means to connect said manifold to the interior of said sudden pressure relay; power means; timing means; first circuitry means including selector switch means to connect said

power means to said first circuitry means to simultaneously energize and open said first solenoid valve and energize and start said timing means; and means to de-energize said timing means responsive to expansion of said bellows; second circuitry means including first and second sub-relays; said selector switch means being adapted to disconnect said first circuitry means and to connect said second circuitry means to said power means to simultaneously energize said first and second sub-relays, said second sub-relay being delay acting; first and second pairs of contacts, said first sub-relay opening said first pair of contacts to deactivate said timer, said second sub-relay closing said second pair of contacts to energize and open said second solenoid valve; a third pair of normally closed contacts in series between said first and second sub-relays adapted to be opened by said delay acting second sub-relay to deenergize said first sub-relay, close said first contacts to start said timing means, and open said second contacts to close said second solenoid valve; and means to deactivate said timer responsive to contraction of said bellows.

7. In a gas filled, positive pressure operated transformer sudden pressure relay of the class described, and having relay means adapted to be actuated by expansion and contraction of a bellows responsive to changes of pressure within said relay, apparatus for testing the performance of said bellows and relay means comprising: a preset solenoid operated valve connected to the interior of said sudden pressure relay; timing means; circuitry including means to simultaneously actuate said valve to the open position and to start said timer; and means to stop said timer responsive to actuation of said relay means by expansion of said bellows.

8. In a gas filled, positive pressure operated transformer sudden pressure relay of the class described and having relay means adapted to be actuated by expansion and contraction of a bellows responsive to changes of pressure within said relay, apparatus for testing the performance of said bellows and relay means comprising: a first preset solenoid operated valve connected to the interior of said sudden pressure relay; timing means; circuitry including means to simultaneously actuate said valve to the open position and to start said timer; and means to stop said timer responsive to actuation of said relay means by expansion of said bellows; a second solenoid operated preset valve connected to the interior of said sudden pressure relay; circuitry including means to simultaneously actuate said second valve to the open position and to deactivate said timer; means including said relay means energized responsive to the expansion of said bellows to close said valve and to start said timer; and said relay means being deenergized by the contraction of said bellows to stop said timer.

9. In a gas filled, positive pressure operated transformer sudden pressure relay of the class described having bellows responsive to changes of pressure within said relay; relay means controlling the actuation of a plurality of relay contacts, and said relay means being adapted to be closed and opened responsive to the expansion and contraction of said bellows, the improvement in apparatus for testing the performance of said bellows and said relay means comprising: a preset solenoid operated valve connected to the interior of said sudden pressure relay; timing means; circuitry including monitoring means in series with said relay means and said relay contacts; means to simultaneously actuate said valve to the open position and to start said timer; and means to stop said timer responsive to actuation of said relay means by expansion of said bellows.

10. In a gas filled, positive pressure operated transformer sudden pressure relay of the class described having bellows responsive to changes of pressure within said relay; relay means controlling the actuation of a plurality of relay contacts, and said relay means being adapted to be closed and opened responsive to the expansion and

contraction of said bellows, the improvement in apparatus for testing the performance of said bellows and said relay means comprising: a preset solenoid operated valve connected to the interior of said sudden pressure relay; timing means; circuitry including monitoring means in series with said relay means and said relay contacts; means to simultaneously actuate said valve to the open position and to start said timer; and means to stop said timer responsive to actuation of said relay means by expansion of said bellows; a second solenoid operated preset valve connected to the interior of said sudden pressure relay; circuitry including means to simultaneously actuate said second valve to the open position and to

5

10

deactivate said timer; means including said relay means energized responsive to the expansion of said bellows to close said valve and to start said timer; and said relay means being deenergized by the contraction of said bellows to stop said timer.
